(57) **CLAIM**

I claim the ornamental design for a two-sided literature holder, as shown and described.

DESCRIPTION

FIG. 1 is a right front corner perspective view of the two-sided literature holder in its fully extended upright position.

FIG. 2 is a right-side view thereof.

FIG. 3 is a front view thereof.

FIG. 4 is a right rear corner perspective view thereof.

FIG. 5 is a top plan view thereof.

FIG. 6 is a bottom view thereof.

FIG. 7 is a left front corner perspective view of the two-sided literature holder in its collapsed position.

FIG. 8 is a right side view thereof.

FIG. 9 is a right front corner perspective view thereof.

FIG. 10 is a front view thereof; and,

FIG. 11 is a top plan view thereof.
